VACUUM CLEANER

Erik Oskar Hansson, Stockholm, Sweden, assignor to Electrolux Corporation, Dover, Del., a corporation of Delaware

Application October 16, 1933, Serial No. 693,724
In Germany April 4, 1933

10 Claims. (Cl. 248—26)

My invention relates to vacuum cleaners and more particularly to means for resiliently mounting a motor-fan unit in the casing of the cleaner.

In Patent No. 1,860,885 granted May 31, 1932, there is disclosed means for resiliently mounting the motor-fan unit which comprises coil springs adapted to be stressed in a direction at right angles to the axes of the springs by the weight of the motor-fan unit. This arrangement of the springs whereby they are stressed at right angles to their axes has been found to be very satisfactory for absorbing vibrations caused by the operation of the motor-fan unit and preventing the transmission thereof to the casing. However, the axes of the springs disclosed in the above patent are parallel to the axis of rotation of the motor-fan unit. The result is that forces acting parallel to the axis of the unit also act parallel to the axis of the springs and, hence, not at right angles thereto. Such forces result from the reaction of the fan against the air stream produced thereby, or if the cleaner unit should be accidentally dropped on one end thereof.

One of the objects of my invention is to so arrange the springs supporting the motor-fan unit that they will be stressed in directions at right angles to their axes both by forces resulting from the weight of the unit and by forces acting parallel to the axis of the unit.

Further objects and advantages of my invention will be apparent from the following description considered in connection with the accompanying drawings, which form a part of this specification, and on which:

Fig. 1 is a side view, chiefly in cross-section, of a preferred embodiment of my invention;

Fig. 2 is an end view of the device shown in Fig. 1 with certain of the parts removed;

Fig. 3 is a cross-sectional view on an enlarged scale taken on the line 3—3 of Fig. 2;

Fig. 4 is a cross-sectional view on an enlarged scale taken on the line 4—4 of Fig. 2;

Fig. 5 is a side view, chiefly in cross-section, of my invention applied to a modified type of vacuum cleaner; and

Fig. 6 is a cross-sectional view on an enlarged scale of a spring support shown in Fig. 5.

Referring more particularly to Figs. 1 through 4, reference character 10 designates the cylindrical barrel portion of a vacuum cleaner casing. Suitably secured to one end of barrel 10 is a ring 11. An end member 12 is adapted to be clamped to ring 11 by means of suitable spring clips 13 or the like. Member 12 is provided with a centrally threaded aperture 13 into which may

be screwed a coupling member 14. Coupling 14 likewise has a central aperture adapted to receive one end of a flexible hose 15, the other end of which may be connected to a suitable dust collecting nozzle 16. A rigid hollow handle member 17 may be interposed between the hose 15 and the nozzle 16.

Secured to the other end of barrel 10 is a ring 18. A ring 19 is secured to ring 18 by means of a plurality of bolts 20. Ring 19 supports an electric motor 21 in a manner which forms the subject matter of the present invention, and which will be described later. Motor 21 is provided with an armature shaft 22 upon which is mounted a fan comprising one or more rotors 23. Rotors 23 are surrounded by a cylindrical housing 24 supported by ring 19. An intermediate wall 25 comprising part of the fan housing is located between the two rotors while a forward wall 26 is located ahead of the first rotor. Both of these walls have central apertures and the aperture in wall 26 is protected by means of a perforated guard plate or the like 27.

Located within the casing between the fan chamber and the end member 12 is a dust bag 28. Bag 28 comprises a suitable cloth bag which permits the passage therethrough of air but is substantially impervious to dust. This cloth bag is secured to a ring 29 having a radially extending flange 30. Flange 30 is provided with a suitable packing ring and is clamped between end member 12 and ring 11.

Secured to ring 19 by means of bolts 31 is a motor guard 32 provided with a plurality of apertures 33 therethrough. A rear closure member 34 is adapted to be slipped over a cylindrical portion of motor guard 32 and to be held in place by means of spring clips or the like similar to those shown at 13. Member 34 is provided with a centrally threaded aperture 35 which is adapted to receive coupling member 14 when the device is used for blowing. A plurality of inclined louver members 36 are preferably arranged adjacent to opening 35 and serve to direct the air discharged therethrough upwardly. A filter 37 may be arranged within member 34 so that all of the air passing through the casing must pass through the filter.

The cleaner unit is adapted to be supported on a horizontal surface by means of a pair of parallel runners 38 secured at one end to ring 11 and at the other end to ring 18. A handle 39 is provided for carrying the unit and a switch 40 serves to control the operation of the motor.

Ring 19 is provided with a plurality of pairs

of lugs 41. In the embodiment shown three pairs of these lugs are equidistantly spaced around the inner circumference of the ring. As appears more clearly from Fig. 3, each of the lugs 41 is formed with a semi-cylindrical recess 42. A clamping member 43 is adapted to be secured to each lug 41 by means of a bolt 44. Clamping members 43 are likewise provided with semi-cylindrical recesses 45 which match up with recesses 42 in lugs 41 to form cylindrical recesses. These cylindrical recesses are adapted to receive and hold socket members 46 which are preferably made of rubber. Motor 21 is provided with a plurality of lugs 47, each one of which is arranged to extend between pairs of lugs 41. Lugs 47 are formed with apertures therethrough which are preferably threaded. A spiral spring 48 is adapted to be threaded into the aperture in lugs 47, as is clearly shown in Fig. 3. The ends of springs 48 are received in sockets 46 which are clamped in the recesses formed by lugs 41 and clamping members 43.

It is preferable that springs 48 be maintained under stress in a direction parallel to their axes and hence tension rods 49 are provided. These rods are formed with slots 50 adjacent their ends, into which slots the ends of springs 48 are hooked. The relative lengths of springs 48 and rods 49 are such that the latter may maintain the former under tension.

The operation of the above described device is as follows:

Upon rotation of the rotors 23 by the motor 21, air is caused to be drawn in through nozzle 16, hollow handle 17, hose 15, coupling member 14 and end member 12 into the dust bag 28. If nozzle 16 is passed over a dusty surface, this air will carry dust into the bag. Here the dust will be deposited while the air will pass through the material of the bag and will be discharged by the fan over and around motor 21, thus cooling the motor. The air then passes through openings 33 in guard 32 and through filter 37 and out through opening 35.

The rotation of the armature shaft 22 and rotors 23 causes a certain amount of unavoidable vibration to be set up in the motor-fan unit. If this vibration were communicated to the barrel 10 or other parts of the casing, undesirable noises would result. By the provision of my improved spring supporting means substantially all of this vibration is absorbed.

The rotation of rotors 23 tends to move the air from left to right, as viewed in Fig. 1, and hence reaction forces tending to move the motor-fan unit from right to left are set up. Due to the arrangement of the springs 28 tangentially with respect to the circumference of the motor 21, these forces act at right angles to the axes of the springs. Also, the weight of the motor-fan unit also acts at right angles to the axis of the lowermost spring and has a component acting at right angles to the axes of the other two springs. Thus, all of the forces normally present act in directions substantially at right angles to the axes of the springs. Furthermore, should the cleaner unit be accidentally dropped on either of its ends, the large forces acting on the motor supports by reason of the resulting shock would also act at right angles to the axes of the springs.

In Figs. 5 and 6 my invention is shown as applied to a vacuum cleaner in which the axis of rotation of the motor-fan unit is vertical. Reference character 51 designates a vertically ar-

ranged casing provided with an upper closure member 52 having an inlet opening 53 and a handle 54. Suitably secured within casing 51, as by having its upper end clamped between the upper end of the casing and cover 52, is a dust bag 55. The lower end of casing 51 is supported on a base member 56. Located within base member 56 and within the lower part of casing 51 is an electric motor 57 having a vertically arranged armature shaft on which is mounted one or more fan rotors 59.

Base member 56 is provided with a plurality of inwardly extending brackets 60 which serve as supports for the motor-fan unit. As is more clearly shown in Fig. 6, brackets 60 are formed with apertures therethrough, a portion 61 of which is comparatively large while a portion 62 is smaller and is threaded to receive a bolt 63. Base 56 is provided with apertures 64 axially in line with the apertures in brackets 60. Bolt 63 is provided with a collar 65 adjacent to its threaded end and with a washer 66 adjacent to the other end. A spring 67 is arranged around bolt 63 and has the portions at one end thereof reduced in diameter so as to bear against the face of collar 65. The portion at the other end of spring 67 is enlarged in diameter sufficiently so that it will not pass through apertures 64 and is clamped between the outside of the base member and washer 66. Thus, as bolt 63 is screwed into threaded aperture 62, spring 67 is placed under tension.

Motor 57 is provided with brackets 68 having apertures 69 therethrough. Brackets 68 are so located that apertures 69 are in line with apertures 61 and 64. Apertures 69 are preferably provided with sleeves 70 of soft rubber or the like.

Bolts 63 with springs 67 thereon are adapted to be inserted through aperture 64 in the base member, through apertures 69 in the brackets 68, into apertures 61, and the end of the bolt threaded into apertures 62. Thus, the motor-fan unit is resiliently supported on the spring 67 and the weight of the unit acts to stress the springs in a direction at right angles to their axes.

Nuts 71 are adapted to be threaded on to springs 67 and tightened against opposite sides of brackets 68 in order to prevent lateral movement between the springs and the brackets.

Base member 56 is provided with a suitable outlet 72. In operation, the rotation of the rotors 59 causes air and dust to be drawn into opening 53. The dust is deposited in dust bag 55 while the air passes therethrough and is discharged from the fan through and around the motor and out through opening 72.

The operation of the motor-fan unit sets up vibrations which are absorbed by the springs 67. In this embodiment the forces on spring 67 resulting both from the weight of the motor-fan unit and the tendency of the fan to displace the unit in a direction parallel to the axis of rotation, act upon the springs in a direction perpendicular to their axes. Also, should the unit be dropped on its end, the resulting shock will act at right angles to the axis of the spring 67.

It will thus be seen that in both modifications practically all of the forces which may occur act on the supporting springs in directions substantially at right angles to the axis of the springs. Inasmuch as the springs are designed to be subject to force acting in this direction, they will efficiently absorb the vibrations and/or shocks.

resulting from these forces. While there have been shown three springs in each of the modifications, it is apparent that other numbers of springs may be employed.

5 While I have shown and described two more or less specific embodiments of my invention, it is to be understood that many variations thereof fall within the scope of the invention, which is to be limited only by the appended claims considered in connection with the prior art.

10 What I claim is:

1. In a vacuum cleaner including a cylindrical casing and a motor, a plurality of coil springs for resiliently supporting said motor in said casing, and means for securing one lengthwise portion of each of said springs to said motor and other lengthwise portions of each of said springs to said casing so that said springs are stressed in direction perpendicular to their axes by forces 15 acting on said motor parallel to the axis of said casing.

2. In a vacuum cleaner including a cylindrical casing and a motor, a plurality of coil springs for resiliently supporting said motor in said casing, and means for securing one lengthwise portion of each of said springs to said motor and another lengthwise portion of each of said springs to said casing so that forces acting on said motor parallel to the axis of said casing and a component of the force resulting from the weight of 20 said motor act to stress said springs in direction perpendicular to their axes.

3. In a vacuum cleaner including a cylindrical casing and a motor, a plurality of coil springs for resiliently supporting said motor in said casing, and means for securing one lengthwise portion of each of said springs to said motor and another lengthwise portion of each of said springs to said casing so that the axes of said springs are tangent 25 to a circle concentric with the axis of said casing and lie in a plane perpendicular to the axis of said casing.

4. In a vacuum cleaner including a cylindrical casing and a motor, a plurality of coil springs for resiliently supporting said motor in said casing, means for securing the ends of said springs to said casing with the axes of said springs lying in a plane perpendicular to the axis of said casing, and means for securing the central parts of said 30 springs to said motor.

5. In a vacuum cleaner including a cylindrical casing and a motor, a plurality of coil springs for resiliently supporting said motor in said casing, said casing being formed with a plurality of pairs 35 of cylindrical recesses having their axes in a plane

perpendicular to the axis of said casing for receiving the end turns of said coil springs, and a plurality of lugs secured to said motor and provided with cylindrical apertures for receiving the central turns of said coil springs.

6. In a vacuum cleaner including a cylindrical casing and a motor, a plurality of coil springs for resiliently supporting said motor in said casing, and means for securing one lengthwise portion of each of said springs to said motor and another 10 lengthwise portion of each of said springs to said casing so that said springs are tangential to said motor.

7. In a vacuum cleaner including a cylindrical casing and a motor, a plurality of pairs of lugs 15 extending inwardly from said casing, each of said lugs formed with a semi-circular groove therein, clamping members formed with similar semi-circular grooves, means for securing a clamping member to each of said lugs so that the groove 20 in the lug and in the member together form a cylindrical recess, a coil spring for each pair of lugs having its ends received in said recesses, and means for securing the central part of each spring to said motor.

8. In a vacuum cleaner including a cylindrical casing and a motor, a plurality of coil springs for resiliently supporting said motor in said casing, a plurality of apertured lugs on said motor, the axes of said apertures being tangential to said motor, 30 threads formed in the apertures having substantially the same pitch as the turns of said coil springs whereby said springs may be screwed into said apertures and held in place therein, and means for securing the ends of said springs to 35 said casing.

9. In a vacuum cleaner including a cylindrical casing and a motor, a plurality of coil springs for resiliently supporting said motor in said casing, means for securing the ends of said springs to 40 said casing with the axes of said springs tangent to a circle concentric with the axis of said casing and lying in a plane perpendicular to the axis of said casing, and means for securing the central parts of said springs to said motor.

10. In a vacuum cleaner including a cylindrical casing and a motor, a plurality of coil springs for resiliently supporting said motor in said casing, means for securing the ends of said springs to said casing with the axes of said springs extending 50 radially with respect to the axis of said casing and lying in a plane perpendicular to the axis of said casing, and means for securing the central parts of said springs to said motor.

ERIK OSKAR HANSSON. 55
